Marin Penn

UNITED STATES PATENT OFFICE.

WILLIAM GLATTES, OF NEW YORK, N. Y.

VARIABLE-STROKE PUMP.

Application filed February 1, 1926. Serial No. 85,082.

This invention relates to motor power transmission and has as its main object to provide a device that will eliminate the present chain or shaft drives.

5 A feature of the invention is in the provision of a rotary motor used to propel a self-contained power vehicle. Another object is in the provision of a pump used to force liquid into a rotary 10 motor.

A further feature is to provide a propelling means that is smooth and substantially noiseless in operation, due to the elimination of gears, chains and shaft drives.

15 These and other equally important objects are accomplished by the novel construction, combination and arrangement of parts hereinafter described and illustrated in the accompanying drawings, forming an 20 essential part of this disclosure, and in which:

Figure 1 is a side elevational view of a conventional type of motor car, parts being broken away to show the position of the 25 transmission mechanism disclosed herein.

Figure 2 is a partial longitudinal sectional view of the clutch device showing the manner in which the same controls the pump, drawn to an enlarged scale.

30 Figure 3 is a fragmentary sectional view taken on line 3—3 of Figure 2.

Figure 4 is a similar view taken on line 4—4 of Figure 2.

35 Figure 5 is a cross-section taken on line 5—5 of Figure 2.

Figure 6 is a perspective view of the wedge-shaped adjusting block.

40 Figure 7 is a perspective view of the adjustable crank actuated by the block shown in Figure 6.

Figure 8 is a transverse sectional view of the pump taken on line 8—8 of Figure 2.

Figure 9 is a transverse sectional view taken on line 9—9 of Figure 11.

45 Figure 10 is a similar view taken on line 10—10 of Figure 11.

Figure 11 is a longitudinal sectional view taken on the centerline of the rear axle.

50 Figure 12 is a sectional view taken on line 12—12 of Figure 1.

Figure 13 is a fragmentary sectional view taken on line 13—13 of Figure 11.

Referring more in detail to the drawings, the numeral 25 generally designates the chassis of a conventional type of automobile.

Intermediate the sides of the chassis and rear of a motor 26 is a casing 27. Leading from the motor and rotatable by it, is a shaft 28 entering into the casing 27. Slidely set in the shaft 28 within the casing 27 is a wedge-shaped adjusting block 29 having an inclined plane 30 at one end and a notch forming a lug 31 at the other end. At the far end of the shaft 28, relative to the motor, is a head 32 formed thereon having therein a recess 33. Set in the head 32 is an adjustable crank 34 having an inclined plane 35 engageable with the wedge 30 of the block 29 and a squared portion 36 to fit in the recess 33 of the head 32.

Slidably and rotatably mounted on the shaft, intermediate the motor 26 and casing wall 37 is a collar 38 having loosely mounted at its lower end, a pawl 39 engageable with a ratchet bar 40 firmly secured to the chassis floor 25.

Rigid in the collar 38 at its outer edges and passing through a packing ring 41 bolted in the wall 37 of the casing are two rods 42 having coiled thereabout springs 43 abutting against the packing ring 41 and the collar 38. The other ends of the rods 42 are rigidly set in another collar 44 having in it a recess 45 to allow the block to engage therewith by means of the lug 31, best seen in Figure 2; the collar 44 being slidably and rotatably mounted on the shaft 28. Abutting against the outer surface of the collar 38 is a fork 46 formed from a pedal 47 actuated by the foot of an operator seated in the car, the pedal being pivoted at 48 on a bracket 49 secured to the casing of the motor 26.

Connected near the gripping end of the pawl 39 is a rod 50 attached to a second pedal 51; the pedal pivoting at 52 on a bracket 53 also secured to the casing of the motor 26 and also being actuated by the foot of an operator in the car.

Rotatably mounted on the crank 34 is a triangularly shaped plate 54 having pivoted at its apexes rods 55. Jointed at the ends of the rods are shanks 56 of pistons 57; the pistons fitting in cylinders 58 bored in the casing 27 and having therein a plurality of valves 59.

Surrounding the cylinders 58 is a channel 60 cored out of the casing 27. Between the cylinders 58 and the channel 60 is positioned a plurality of valves 61. Set in the casing 27 is a plurality of stoppers 62 and 62'. Leading rearwardly from the lower stopper 62' is a pipe 63 connected with the propelling means located on the rear axle of the vehicle. A return pipe 63' from the propelling means enters the casing 27 at the forward top narrow portion 64 of the casing. Both pipes 63 and 63' are in two parts connected together by means of couplings 65 and 65'.

Centrally mounted on the rear axle, the same being in two parts 66 and 66' obviously to allow the vehicle to turn, is a casing 67 having an inlet 68 from the pipe 63 at the forward end and an outlet 69 to the pipe 63' at the rear end.

Mounted on the axles 66, 66' within the casing 67 are two pairs of rotors 70 and 70', and 71 and 71' having vanes respectively 72 and 72', and 73 and 73' pressed outwardly by the action of flat springs 74.

Fixed in recesses 75 in the rotors 70, 70', 71 and 71' is a plurality of pins 76, 77, 78 and 79 to engage with similar pins 80, 81, 82 and 83 respectively in discs 84, the discs being slidable on keys 85 in grooves 86 in the axles 66, 66' and having annular recesses 87 in their outer peripheries.

Surrounding the rotors 70, 70', 71 and 71' are channels 88 and 89 into which the vanes 72, 72', 73 and 73' project, the channels having openings respectively 90 and 91 to the main inlet 68 and openings 92 and 93 to the main outlet 69.

Journalled in the forward portion of the casing 67 are rods 94 having mounted on their outer ends, gears 95 to engage a slideable rack 96.

Secured to the rods 94 to cover the openings 90 or 91 are shutter valves 97 operable by the rotation of the rods, the same being for the purpose of moving the vehicle forward or in a reverse direction as will later be seen.

The other end of each rod 94 is formed into an eccentric as at 99 to engage the annular recess 87 in the slideable discs 84 and by rotation, slide the discs on the axles 66, 66' as may be desired.

In operation the casing 27 is filled with oil or other heavy liquid and the shutter valves 97, in going forward, are positioned as they are in Figure 11, being controlled in an obvious manner by the operator.

When the motor in the casing 26 is start-

ed, in a manner similar to the conventional motor in self-propelled vehicles, the shaft 28 rotates causing the block 29 and the crank 34 to also rotate, the crank revolving within the triangular plate 54.

To put the car in motion, the brakes are released and the clutch pedal 47 is gradually pushed down by the foot of an operator. This causes the collar 38 to slide toward the rear, which action is given to the collar 44, the same being engaged with the block 29, slides the block in the shaft 28. The wedged portion of the block 29 causes the crank 34 to move outward in the recess 33 of the head 32, taking the plate 54 off the centerline of the shaft 28 and imparting to the same a gyroscopic motion; this motion bringing the pumps into action.

When the lower piston 57 is moving up, the valves 59 are opened by the oil pressure, allowing the oil to get in the lower portion of the cylinder 58. On the downward stroke, the valves 59 close and the oil in the cylinder is forced through the valve 61 into the channel 60 from which it enters the pipe 63, going to the rear of the car into the inlet 68.

From here the oil enters the openings 90 into the channels 88, impinging against the vanes 72 of the rotors 70 and 70', causing the same to rotate. The rotors being connected to the axles 66, 66' by means of engagement with the discs 84 and by the pins 76, 77, 80 and 81, imparts a revolving motion to the same, causing the vehicle to move.

The further the pedal 51 is pressed downward, the further off center the plate 54 is moved and therefore the stroke of the pistons 57 is longer and more powerful, giving greater velocity to the oil and hence more speed to the car.

To move the vehicle in a reverse direction, it is first brought to a full stop. The valves 97, operated by the driver, are then caused to open the channels 89 and close 88, the same mode of driving being employed as above described. However, the oil now enters channels 89 instead of 88 and impinges against the vanes of the rotors 71 and 71' in an opposite manner to 70 and 70'. The discs 84 now engage pins 78, 79 of the rotors 71 and 71', the same being actuated by the turning of the eccentric 99. This causes the axle 66, 66' to rotate in a reverse direction, moving the vehicle rearwardly. Acceleration is caused in the same manner as above described.

As changes of details of construction could be made within the scope of the appended claim, it is intended that all matter contained in the foregoing description or shown in the accompanying drawings, shall be interpreted as illustrative and not in a limiting sense.

Having thus described my invention, what

I claim as new and desire to secure by Letters Patent, is:—

A motor transmission system comprising a casing containing a liquid, cylinders in said casing, a longitudinally grooved shaft in said casing, an adjustable wedge block slideable in said groove, an adjustable crank in said groove actuated by said block said crank being normally concentric with said shaft, a

triangular plate pivotally mounted on said crank, pistons in said cylinders connected to the apexes of said plate, and resilient means slideable in said casing to move said crank eccentric with said shaft to impart a gyroscopic motion to said pistons. 10

In witness whereof I have affixed my signature.

WILLIAM GLATTES.
